UNITED STATES PATENT OFFICE

2,487,696

COMBINATION TOOL AND HANDLE

Fredrick W. Coffing, Danville, Ill., assignor to Coffing Hoist Company, Danville, Ill., a corporation

Application December 6, 1947, Serial No. 790,178

6 Claims. (Cl. 306-6)

1

This invention relates to a combination tool and handle.

The chief object of the present invention resides in providing a two socketed handle, complementary formed shank provided tools, and a singular anchor member identically bearing upon the handle when selectively associated with a tool shank depending upon which handle socket the shank then occupies.

The chief feature of the present invention resides in forming the sockets and the shanks of a frusto-polygonal character whereby the tools may be disposed in either socket and non-rotatably retained therein; the anchor member effecting a wedging of the shank in the selected socket.

Other objects and features of the invention will be set forth more fully hereinafter.

The full nature of the invention will be understood from the accompanying drawings and the following description and claims.

In the drawings—

Fig. 1 is a perspective view of a handle connector portion, hereinafter termed handle, illustrating the same as having longitudinally aligned and transversely disposed intersecting sockets.

Fig. 2 is a central sectional view thereof with a tool disposed in the so-called transverse socket and illustrated in end elevation.

Fig. 3 is a similar view of the handle with a tool disposed in the so-called longitudinal socket, the tool being illustrated in top plan.

In the drawings 10 indicates an elongated handle portion having therein a tapered tubular socket 11 adapted to receive the tapered end of a wood handle, not shown. Hole 12 is adapted to take a suitable anchor member such as a screw, not shown. The handle 10 includes a head portion 13 provided with a frusto-octagonal inwardly tapered socket 14, the axis of which coincides with the handle axis so that sockets 14 and 11 are substantially aligned.

The head 13 also includes another frusto-octagonal inwardly tapered socket 15 which extends through the head portion and which has its axis disposed transverse to and intersecting the longitudinal axis of the handle. The two last mentioned sockets cross each other or intersect.

In Fig. 2, 16 indicates a tool having a blade portion 17, a shank portion 18, and a reenforcing portion 19. The shank is complementary in form to the socket 15, but when seated therein does not project completely through the same for reasons hereinafter assigned.

Coaxial with said shank is the threaded bore

2

20. A cap screw bolt having head portion 21, cap portion 22, and threaded shank 23 is adapted to have the latter threaded into the shank bore 20; and since cap portion 22 bears upon face 24 of said head 13, the screw draws the shank 18 into socket 15 and wedgingly seats the shank therein. Since the socket is regularly polygonal, the hoe blade may be disposed in other positions than that shown, such as a biased position, or in a position wherein the plane of the tool includes the handle axis. In this position the tool serves as an ax or chopping tool.

Reference will now be had to Fig. 3. Herein a second tool includes a cultivating blade 25 and a stem 26, longitudinally aligned, if desired, with shank 27. This is complementary to socket 14.

Shank 27 includes a transverse threaded bore 28. When this shank is seated in socket 14, the cap screw bolt aforesaid is disposed in the smaller 20 end of socket 15, and eccentrically thereof as shown. The threaded shank 23 is threaded into bore 28 until cap portion 22 again bears upon face 24 of head 13. As shank 27 is drawn upwardly in the direction of the face 24 of the head and in the socket 14, the tapers are such that the shank 27 is wedged home in socket 14.

Thus, the cap screw bolt in either instance has threaded association with a tool shank to wedgingly seat same in the selected socket and also retains the shank in that socket.

The several tools may be cast steel, forgings, and the like. The handle may be of similar material. The only machining required is the drilling and tapping of the tool shanks. The 35 economy of production and simplicity of construction will be self evident from the foregoing description.

While the invention has been illustrated and described in great detail in the drawings and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. In combination an elongated handle having at one end a head portion with a longitudinally disposed inwardly tapering socket opening at that end and a second similar socket disposed transversely of the first socket and intersecting same, a tool having a socket seatable similarly tapering shank, the shank having a threaded bore there-in, and a threaded anchoring member having

threaded engagement with the shank in the threaded bore thereof and disposed in the second mentioned socket and having operative bearing upon the head portion adjacent that socket for drawing the shank into a head socket and wedging holding the shank in the socket.

5

2. Structure as defined by claim 1 wherein each socket is polygonal in cross-sectional character and the tool shank is of complementary character.

3. Structure as defined by claim 1 wherein the said transverse socket extends completely through the head portion.

4. Structure as defined by claim 1 wherein the shank threaded bore of a transverse socket mounted tool is disposed coaxially of the shank.

15

5. Structure as defined by claim 1 wherein the shank threaded bore of a longitudinal socket mounted tool is disposed transversely of the longitudinal axis of the shank of said tool.

6. Structure as defined by claim 1 wherein the

transverse socket bore extends completely through the head portion and the threaded anchoring member is disposed eccentrically of that bore.

FREDRICK W. COFFING.
